Primary Examiner — Karen S Acker(74) Attorney, Agent, or Firm — Meunier Carlin & Curfman LLC(57) CLAIM

The ornamental design for a tile assembly in a mosaic pattern, as shown and described.

DESCRIPTION

FIG. 1 is a front view of a tile assembly in a mosaic pattern according to my new design.

FIG. 2 is right-side view thereof.

FIG. 3 is left-side view thereof.

FIG. 4 is top view thereof; and,

FIG. 5 is a bottom view thereof.

The broken lines depicting unclaimed diagonal webbing which connects the individual tiles and the unclaimed environmental material behind the front of the article form no part of the claimed design. The broken lines illustrating the front of the tile elements depict portions of the tile assembly in a mosaic pattern that form no part of the claimed design.
